UNITED STATES PATENT OFFICE.

EDUARD JACOBUS RYERSON, OF JACKSON, MICHIGAN.

WAIST.

SPECIFICATION forming part of Letters Patent No. 674,179, dated May 14, 1901.

Application filed December 27, 1900. Serial No. 41,190. (No model.)

To all whom it may concern:

Be it known that I, EDUARD JACOBUS RYERSON, a citizen of the United States, residing at Jackson, in the county of Jackson and State 5 of Michigan, have invented certain new and useful Improvements in Waists; and I do declare the following to be a full, clear, and exact description of the invention, such as will enable others skilled in the art to which it 10 appertains to make and use the same.

This invention relates to improvements in waists.

The object of the invention is to provide a waist having a skirt portion constructed and 15 secured thereto in a novel manner, so as to secure the advantages of, first, a greater variety in the styles of making waists; second, a more perfect fit in the upper part of the waist; third, an absolutely perfect fit over 20 the hips and the absence of bulk or folds at this point, and, fourth, the prevention of the working up of the waist from under the dress-bands.

To these ends the invention consists in certain 25 novel features of construction and arrangement of the parts, which will be herein-after more fully described, and particularly pointed out in the appended claim.

In the accompanying drawings, Figure 1 is 30 a front view of a waist embodying my invention. Fig. 2 is a rear view thereof, showing the skirt portion of the waist extended. Fig. 3 is an inside view of the lower rear portion of the waist-body and skirt. Fig. 4 is a vertical cross-section through the connecting edges of the waist-body and skirt. Fig. 5 is 35 a detail view of the skirt detached.

Like reference characters designate corresponding parts throughout the several views.

40 A in the drawings represents the upper portion or body of the waist, and B the skirt or yoke portion thereof. The body A is cut and made in the usual manner, with the exception that it is cut off abruptly at the waist-line, 45 being formed without the usual integral skirt. In accordance with my invention the skirt or yoke B is made up of two or more segmental pieces having their meeting ends cut bias and united by sewing, so as to secure the proper curvature. The drawings show the skirt 50 formed of two such pieces C and D, sewed together at the center d; but, if desired, I may

separate said pieces on the dotted lines e to form four united pieces, whereby a saving in cloth is effected. Each of the pieces C and 55 D is provided with cut-away portions m, which serve to come in contact with the hip portions, whereby the waist will adjust itself in position on the body of the wearer.

The upper edge of the skirt may be united 60 to the lower edge of the body in any suitable manner. To secure the best results, however, I prefer the following ways, either of which may be employed: First, sewing the lower part of the waist to the upper part of 65 the skirt and covering the seam with a band, braid, or any suitable covering; second, placing the edge of the lower part of the waist against the edge of the upper part of the skirt and uniting the two with an upper and 70 under band of suitable material; third, by sewing the lower part of the waist to the skirt in a double seam, commonly known as a "flat" seam; fourth, by tucking the lower part of 75 the waist and placing the upper part of the skirt under the tuck and stitching it down; fifth, by reversing this process and tucking the upper part of the skirt and placing the lower part of the waist under the tuck and stitching it down, or, sixth, by binding the 80 lower part of the waist and upper part of the skirt together with a suitable material and stitching the binding down to the garment.

In the present instance I have shown the lower edge f of the body folded to form a tuck, 85 in which the upper edge g of the skirt is inserted and the two united together and to a strengthening tape or band h on the inside of the waist.

By constructing the parts described in the 90 manner set forth I attain the following advantages: First, a saving of material is effected by forming the skirt in sections and independent of the waist-body; second, a greater variety of styles is afforded in the 95 making of waists, as different styles of bodies may be made without varying the form of the waist-band; third, a better fit of the body is secured, for the reason that the waist portion of the latter may be plaited or tucked, as desired, to attain any required flare without altering the shape of the skirt; fourth, the formation of plaits, gussets, or folds of any kind is obviated. Hence the waist is adapted to 100

fit more perfectly about the hips without gathering or bulging, and, fifth, the waist is effectually prevented from working up from under the dress-bands.

5 It is obvious, of course, that the invention is applicable to the so-called "shirt-waists" for men and boys, as well as ladies' waists, and that both applications fall clearly within the spirit and scope of the invention.

10 Having thus fully described my invention, what I claim as new and useful, and desire to secure by Letters Patent of the United States, is—

A waist having a skirt or yoke secured

thereto, said yoke or skirt consisting of two 15 or more separate segmental sections of equal lengths connected together, the forward sections being cut away to form curves for the hip portions of the wearer, and said waist and yoke being reinforced at their connecting or 20 meeting edges, substantially as specified.

In testimony whereof I have hereunto set my hand in presence of two subscribing witnesses.

EDUARD JACOBUS RYERSON.
